UNITED STATES PATENT OFFICE.

MICHAEL J. ECONOMIDES, OF BROOKLYN, NEW YORK.

ADJUSTABLE WRENCH.

Application filed May 7, 1924. Serial No. 711,688.

To all whom it may concern:

Be it known that I, MICHAEL J. ECONOMIDES, a citizen of the United States, residing at Brooklyn, in the county of Kings and 5 State of New York, have invented certain new and useful Improvements in Adjustable Wrenches, of which the following is a specification.

The present invention relates to an adjustable wrench adapted to grip bolts, pipes, or similar cylindrical objects.

The main object of the invention is to provide such a wrench which may be used to take bolts and pipes of different diameters. For this purpose, the wrench consists of a head member upon which are mounted a pair of wedges provided with gripping teeth. The wedges are mounted so that their gripping faces will advance toward or 15 retract from each other and may be secured in adjusted position. A further object of the invention is to provide a wrench, the head of which is formed of readily separable mating sections so as to permit said 20 head sections to be conveniently positioned around a pipe or a sleeve or nipple thereon for the purpose of removing the sleeve or pipe when the ends thereof are permanently attached to a fixed support.

30 In the accompanying drawings:

Figure 1 represents a top plan view of the preferred form of the invention,

Fig. 2 is a bottom plan view of Fig. 1,

Fig. 3 is a sectional view along line 3—3

35 of Fig. 1,

Fig. 4 is a sectional view along line 4—4 of Fig. 3,

Fig. 5 is a fragmentary sectional view along line 5—5 of Fig. 2,

40 Fig. 6 is a top plan view, partly in section, of a modified form of the wrench,

Fig. 7 is a side elevation of Fig. 6, and

Fig. 8 is a side elevation illustrating the handle employed for operating the wrench 45 shown in Figs. 6 and 7.

Referring first to the preferred form of the invention illustrated in Figs. 1 to 5 inclusive of the drawings, the reference numeral 10 represents the head of the wrench 50 and 11 the gripping jaws slidably mounted thereon. The head 10 consists of two mating halves 12 and 13 provided with dowels 14 for properly positioning the halves together, said sections being readily separable 55 so as to permit the same to be conveniently placed around a pipe or a sleeve or nipple

thereon for the purpose of removing the nipple or pipe when the ends of the pipe are permanently secured to a fixed support.

The head 10 has the shape of a flat-sided 60 cylindrical disc with a central opening 15, the gripping jaws 11 sliding along the flat top surface 16 of the head, as best seen in Fig. 3, and being held in position thereon by means of parallel dovetailed grooves 17 opening through the top surface 16 of the head and engaging correspondingly shaped 65 ribs 18. This groove and rib connection may have either the form illustrated in Fig. 3; that is to say, forming dove-tails, or the 70 grooves may be T-grooves, in which case the ribs 18 will have the same cross section. In any case, the jaws 11 are held in the head in such a manner that they cannot be lifted therefrom, but slide in parallel 75 relation across the same.

As best seen in Fig. 1, the jaws 11 are wedge-shaped, with their outer surfaces 20 lying parallel to each other and to the 80 grooves 17, while the gripping surfaces 19 of the jaws, which surfaces face each other, are inclined with regard to the outer surfaces of the jaws but parallel to each other so that no matter in what position the gripping 85 jaws are set, the gripping surfaces 19, whether advanced toward or retracted from each other, will always remain parallel. The gripping surfaces of the jaws are provided with teeth or roughened in any other 90 suitable manner to obtain a firm hold upon the object to be gripped.

On each of the mating halves 12 and 13 of the head 10 is revolvably mounted a worm 21 and these worms mesh with corresponding worm teeth 22 along the outer surfaces 95 20 of the jaws, as best seen in Fig. 1. By turning the worms 21, it will now be evident that the gripping surfaces 19 of the jaws 11 may be advanced toward each other to firmly hold a cylindrical object 23 therebetween, this object projecting through the central aperture 15 in the base member.

On the under side of the head 10 is shown a strap 24 adapted to hold the mating halves of the head together. Along the 105 outer periphery of the head and near the under side thereof, are ratchet teeth 25 with which a dog 26, swiveled as at 27 upon the ratchet handle 28, is adapted to engage. This dog has two arms terminating with 110 fingers 29 and, depending upon which of said fingers is pressed down, the ratchet

handle 28 will turn the wrench in a clockwise or counter-clockwise direction, in the usual manner. The ratchet handle has an arcuate guide 30 having a T-shaped inner flange 31 engaging in a correspondingly shaped annular groove 32 opening through the cylindrical surface of the head, as best seen in Figures 3 and 5. It will thus be evident that when both fingers of the dog 26 are disengaged from the ratchet teeth 25, the arcuate portion 30 of the ratchet handle 28 may travel in a complete circle around the head 10. When it is desired to remove a pipe section or a nipple connecting pipe sections extending between two fixed parts, the worms 21 are rotated until the reduced ends of the gripping jaws are retracted beyond the line of junction of the head sections, after which said sections are separated and swung laterally with the slotted strap 24 acting as a hinge or pivot. The head sections are then fitted around the pipe or nipple to be removed and the worms 21 caused to engage the teeth on the jaws so as to firmly grip the pipe, when the pipe section or nipple may be conveniently removed by rotating or oscillating the handle of the wrench, as before stated. When the jaws are moved to the gripping position, they extend in crossed relation to the meeting edges of the two sections, and since they fit into grooves formed in the sections they will serve not only as means to grip the pipe or other article disposed in the opening 15 but also serve as locking means to prevent the sections from moving towards an open position.

In the modified form of the wrench illustrated in Figs. 6 and 7, the head 33 is also made in two mating halves 34 and 35 doveled together as at 36, as previously described in connection with the preferred form of the invention. In this case, however, the head is provided with square sectioned grooves 37 which open through the top surface of the head. The depth of these grooves is the same as the thickness of the jaws 38 so that when the jaws are inserted in their respective grooves their top surfaces become level with the top surface of the head 33 and no dove-tail or T-groove is necessary in this case. The jaws 38 are held in position in the grooves by means of a cover or top plate 39 held down by screws 40 on the head 33. As before, the jaws 38 are wedge-shaped, with their gripping surfaces 41 inclined toward the outer surfaces 42 of the jaws so that the gripping surfaces 41 are parallel to each other, and these surfaces are provided with teeth or otherwise roughened as in the preferred embodiment of the device. The width of the grooves 37 corresponds to the greatest width of the jaws 38 and in order to keep the outer surfaces 42 always in contact with the cor-

responding surfaces of the grooves, a stud 43 is provided on the upper side of each jaw engaging in corresponding slots 44 provided in the cover plate 39. The slots 44 extend parallel to the sides of the grooves so that the studs 43 are always guided parallel to the same. 70

Instead of the ratchet handle provided in the preferred construction, a pin handle 45, terminating in a tapered tip 46 on its arcuate portion 47, is furnished. The arcuate portion 47 of the handle is bent to the same radius as the neck 48 on the head 33 and this neck is provided with a series of radially directed sockets or recesses 49 in 80 which the tip 46 of the handle is adapted to engage, as indicated in Fig. 6. 75

Instead of the pin handle 45 or the ratchet handle 28, it is evident that an ordinary open wrench may be used for turning this adjustable wrench, in which case the head of the latter wrench will be provided with a hexagonal or other flattened neck portion. 85

In the embodiment of the device illustrated in Figs. 6 and 7, no adjusting means for the jaws 38 has been shown and the jaws will accordingly be set by hand by pushing them inward to contact with the object to be gripped. It is, however, evident that worm gears similar to the gears 21 and 22 shown in Figs. 1 and 3, may also be provided in this case. 95

Having thus described the invention, what I claim is:

1. A wrench comprising a head provided with an axially disposed opening to receive an article to be turned, said head being formed of mating sections having their end faces meeting along a diameter of the head when in a closed position and said sections being adapted to be moved into and out of a closed position, and common means for gripping an article disposed in said opening and holding said sections in a closed position, said means overlapping both sections when in a locking position. 100

2. A wrench comprising a head provided with an axially disposed opening to receive an article to be turned, said head being formed of mating sections having their end faces meeting along a diameter of the head when in a closed position and said sections being adapted to be moved into and out of a closed position, and a jaw slidably carried by said sections for movement transversely of the meeting edges thereof and when in engagement with both sections adapted to lock the sections in a closed position. 115

3. A wrench comprising a head provided with an axially disposed opening to receive an article to be turned, said head being formed of mating sections having their end faces meeting along a diameter of the head when in a closed position and said sections being adapted to be moved into and out 120

130

of a closed position, and article-gripping jaws carried by said sections at opposite sides of said opening, said jaws adapted to move in crossed relation to the meeting 5 edges of the sections and engageable with the sections to lock them in a closed position.

4. A wrench comprising a head provided with an axially disposed opening to receive an article to be turned, said head being 10 formed of mating sections having their end faces meeting along a diameter of the head when the sections are in a closed position, means connecting said sections for movement into and out of a closed position, said 15 sections provided in the upper faces of their contacting end portions with grooves adapted to register when the sections are closed and provide tracks at opposite sides of the article-receiving opening, jaws slidable in 20 said tracks and adapted to grip an article in said opening, said jaws when engaged in the grooves of both sections serving to lock the sections in a closed position, and means to impart movement to said jaws.

25 5. A wrench comprising a head provided with an axially disposed opening to receive an article to be turned, said head being formed of mating sections having their end faces meeting along a diameter of the head 30 when the sections are in a closed position,

means connecting said sections for movement into and out of a closed position, jaws 35 slidably carried by the end portions of said sections for movement in crossed relation to the meeting faces thereof and when in engagement with both sections serving to lock the sections in a closed position, and means to permit turning of said head when in engagement with an article.

6. A wrench comprising a head provided 40 with an axially disposed article-receiving opening and formed of substantially semi-circular sections, hinge means pivotally connected with one section and slidably and 45 pivotally connected with the other section, said sections being provided in their end portions with grooves to register at their inner ends when the sections are closed and form tracks upon opposite sides of the article-receiving opening, jaws adapted to be 50 slidably mounted in said grooves and movable across the head with their inner side portions overlapping the article-receiving opening, said jaws when in engagement with both sections serving to prevent movement 55 of the sections out of a closed position, and means to move said jaws along said tracks.

In testimony whereof I affix my signature.

MICHAEL J. ECONOMIDES. [L. s.]
